UNITED STATES PATENT OFFICE

LOUIS P. HORNING, JR., OF ELIZABETH, NEW JERSEY, ASSIGNOR TO VICTOR TALKING MACHINE COMPANY, OF CAMDEN, NEW JERSEY, A CORPORATION OF NEW JERSEY

COMBINED PHONOGRAPH AND RADIO APPARATUS

Application filed July 27, 1922. Serial No. 577,941.

This invention relates to a combined phonograph and radio apparatus, and has for its primary object to combine such instrumentalities in cooperative relation, with 5 in a single cabinet.

Another object is to provide in such apparatus a common amplifier, having communication both with the phonograph mechanism and the radio apparatus, and in which either 10 the phonograph mechanism or the radio apparatus may be used at will, either separately or in combination.

Still another object of the invention is to construct a phonograph cabinet in such manner, that the lower portion thereof, commonly utilized as a record-storing space, may be employed to carry the radio apparatus.

A further object is to so construct and arrange the cabinet and mechanism, that the 20 phonograph will not lose its identity as such, and at the same time, the apparatus will be thoroughly reliable and efficient for radio use.

A still further object is to so construct the 25 radio apparatus that it will be conveniently accessible for repair or replacement of parts, and particularly to enable the batteries to be removed without removing or disturbing the other parts.

It is also an object to provide a cabinet construction in which the radio parts may be concealed when in use, so that the same 30 will be protected and will have the appearance of an ordinary cabinet phonograph. To 35 this end, the radio apparatus in the present embodiment is mounted upon a movable panel adapted to be swung upon hinges, to expose the parts for repair or replacement, and which, when not in use, is concealed behind outer swinging doors.

Still another object is to provide a radio apparatus in combination with the amplifying horn of a phonograph, and which is particularly adapted to produce sounds which, 45 when amplified in the horn, will be emitted with their natural volume and quality, and without the necessity of, in any way, changing the horn in its characteristics for phonograph amplification.

With the above and other objects in view,

an embodiment of the invention is shown in the accompanying drawings, and this embodiment will be hereinafter more fully described with reference thereto, and the invention will be finally pointed out in claims. 55

In the drawings—

Fig. 1 is a vertical sectional view of a cabinet, embodying a phonograph mechanism combined with a radio apparatus and a common amplifier, constructed in accordance with the present invention; 60

Fig. 2 is a detail sectional view of a portion of the sound-conveying tubes and sound-amplifier, formed according to a modification of the invention, in which the apparatus is 65 adapted for recording or for sending sound, either from the phonograph or the radio-receiving apparatus;

Fig. 3 is a perspective view of a modification, having doors for concealing the radio 70 apparatus and showing the same closed, that is, when the radio apparatus is not in use;

Fig. 4 is a similar view, and showing the outer doors opened to expose the radio-control panel; 75

Fig. 5 is another perspective view, and showing the radio-control panel swung outwardly to expose the parts of the apparatus carried upon its inner side, and the connections to the batteries and radio receiving 80 member;

Fig. 6 is a horizontal sectional view along the line 6—6 of Fig. 3; and

Fig. 7 is a wiring plan of the particular radio apparatus employed. 85

Referring to the drawings—

The cabinet 5 is of the usual phonograph type, and is divided by a partition 6 (Fig. 1), into an upper amplifier-containing compartment 7 and a lower compartment 8. An amplifier 9 of the horn type is mounted in the compartment 7, its forwardly diverging end opening in a sound outlet 10, in which there are disposed a plurality of pivotally mounted shutters 11, adapted to control or regulate the volume of sound emitted. At its inner end, the horn is connected by a tapered tubular portion 12 to the tone-arm 13 of the phonograph mechanism, mounted upon the motor-board 14. This mechanism is mount- 90
95
100

ed upon the upper side of the cabinet, and is adapted to be normally closed by a hinged lid 15.

The tubular portion 12 is curved laterally from its upper end connected to the tone-arm, 5 into connection with the end of the amplifying horn, and has integrally formed therewith a downwardly extending tapered tubular portion 16, extending through an opening 50 of the partition 6, and being curved at its upper 10 end in substantial continuity with the passage through the amplifying horn, and in opposed relation to the tubular portion 12, which is also curved in substantial continuity with 15 said passage. The opening 50 has its walls out of contact with the tubular portion 16, so that the whole sound-conducting and amplifying structure is supported from the motor-board. The acoustical advantage of this is 20 that said structure is free from contact with the partition 6, and will, therefore, neither transmit vibrations to nor receive vibrations from the cabinet structure, particularly that 25 part of the structure carrying and housing the radio apparatus, which would be deleteriously affected by said vibrations. At the point 30 of connection of the tubular portions 12 and 16, the contiguous portions thereof form a sound-guiding baffle, or web, 17, adapted to 35 guide the sound emanating from the sound-reproducer of the phonograph mechanism to the amplifying horn, after passing downwardly through the tubular portion 12; and, 40 on the other hand, directing the sound emanating from the radio-receiving member 18 into the amplifying horn, after passing upwardly through the tubular portion 16. The 45 amplifying horn is sound insulated from the tubular portions 12 and 16, by means of a gasket 51, of rubber, felt, or other suitable insulating material, held between the flanged portions 52 and 53, and secured by bolts 54. Metallic vibration, generated within the walls 50 of the tubes 12 and 16, is thus prevented from being transmitted to and amplified in the horn.

At the lower end of the portion 16, there is secured a receiver 18 for the radio apparatus, which may be of any suitable type, such 55 as a Magnavox unit.

The radio apparatus is mounted upon a front panel 19, disposed at the forward side of the compartment 8, and either bodily removable, or hingedly mounted, as shown, in 55 the manner of a door, to permit of convenient access to the apparatus within the compartment, (see Fig. 5). The panel 19 (Fig. 1) may have its front face constructed of wood, to correspond with the general finish of the 60 cabinet, and it is preferably backed by a panel-board 20 of suitable insulating material—such, for example, as bakelite.

The horn 9 is of the usual size and proportion to produce a proper reproduction of photographic sound, and it has been discovered,

as a part of this invention, that by means of the particular arrangement of radio apparatus employed, this same horn can be used to efficiently amplify the sound produced through radio communication, without, in any way, changing the horn as regards its necessary and inherent characteristics for phonograph amplification.

In particular, the radio apparatus, employed herein, is shown diagrammatically in the wiring plan (Fig. 7), and the parts themselves are illustrated in the several views of the cabinet. The several elements of the radio apparatus are mounted upon the inner side of the panel-board 19, and comprise an audion bulb 21, a variable condenser 22, two variometers 23 and 43, a variocoupler 24, a resistance 44, a grid condenser 45, and a switch 46 connected in the circuit, between the filament of the audion bulb and the positive side of the "A" battery. A "B" battery 31 is also provided in the circuit. Upon the rear wall of the cabinet, there are secured terminals 32, by means of which the apparatus is connected to the antenna, or aerial, and the ground. These various elements of the radio apparatus are connected by suitable wiring, and are adapted to be controlled and adjusted by means of exposed knobs 25, provided upon the panel-board, as is usual in radio apparatus.

It has been found, in practice, that the radio-receiving apparatus,—arranged and constructed in accordance with this invention, and which may be characterized as having one stage of audio-frequency,—combined with the receiver of the "Magnavox" type, is peculiarly suited to generating radio-communicated sound which, when subjected to the further amplification provided by the phonograph-type horn 9, is emitted from the apparatus with full volume and tone quality, and in its true and natural phonetic values. Thus, the horn, while maintaining its phonograph characteristics, is adapted to efficient use with the radio apparatus.

In the embodiment disclosed in the drawings, the panel 19, mounting the radio apparatus, is set back in the cabinet, and is hinged along one side at 26 to a side frame portion 27, (Fig. 6), also set inwardly from the side wall of the cabinet; and in front of the panel there are hinged to the front edges of the side walls a pair of doors 28 and 29, similar to the doors used in the ordinary phonograph for housing the record compartment, adapted to normally cover or conceal the radio-panel when the apparatus is not in use. Fig. 3 shows the closed position of the doors, and in which the apparatus has the appearance of an ordinary phonograph cabinet.

Fig. 4 shows the position with the doors 28 and 29 opened to expose the radio-panel, preparatory to "tuning in" to receive a radio message; and Fig. 5 shows the radio-panel

swung to open position, and in which position the various parts of the apparatus are conveniently accessible for repair or replacement.

5 The rear wall 33 of the cabinet is hingedly mounted at 34 (Fig. 6), to permit access to the interior of the radio compartment from the rear, and particularly so that the batteries may be readily removed for re-charging or 10 change, without disturbing the other parts of the apparatus.

The invention provides a combination phonograph and radio apparatus, in which either or both may be operated at will, and 15 independently of the other, and in which the sound-amplifying horn is common to both—thereby providing a compact apparatus, completely enclosed by a cabinet, for producing or receiving sound. The shutters 20 11 permit of the control of the sound, either as to its volume or direction. The invention provides, at the same time, a highly scientific sound-producing instrument and a very attractive article of furniture.

25 As herein shown, the radio equipment is for receiving electrical impulses and translating the same into audible sounds which are amplified by the arm 9, and for these purposes I have shown a radio receiving set of a well 30 known type which includes a radio receiver 18 supported by the amplifier member 16 which, as shown, depends from the amplifier 9 into the compartment 8 of the cabinet. The invention is not limited, however, to the 35 use of a radio receiving set in connection with a phonograph mechanism, for the reason that said invention includes, also, a radio sending mechanism by which audible sounds emitted from or reproduced by the phonograph mechanism may be conducted from the reproducer and the tone arm by conduit 12 and 40 through conduit 16 to a microphone supported by said conduit 16, in which case the valve 37 of Figure 2 is adjusted to close the inlet 45 to the amplifier 9, and a microphone replaces the radio receiver 18 of the conduit 16, it being understood that a radio sending equipment is substituted for the radio receiving set herein described and illustrated more 50 particularly in Figures 1, 4, 5, 6 and 7, of the drawings.

In Fig. 2, there is illustrated a modification of the invention, in which the three-way horn—comprising the amplifier 9, its throat or smaller end only being shown in this view, and the tubular portions 12 and 16, extending to the phonograph and radio apparatus, respectively—is provided with a pivotally mounted sound-directing or sound-baffling web 35, which may be turned by means of a knob 36, projecting through to the outside of the cabinet for convenient manipulation, into one or the other of the dotted line positions shown, to direct the sound from either 60 the tubular portion 12 or the tubular por-

tion 16, to the amplifier, as desired. It may also be turned into substantially vertical position, so as to permit of the free passage of sound from one of said tubular portions to the other,—so that, upon occasion, the 70 phonograph reproducing mechanism may be utilized as a sound source for transmitting from the apparatus electrically, in which case the parts within the compartment 8 would be designed for sending purposes, as 75 distinguished from receiving. On the other hand, the sound-reproducing mechanism of the phonograph may be substituted in well-known manner, by a sound-recording apparatus, adapted to record upon a wax record 80 the sounds received by the radio-receiving set. During such operations, the sound-amplifying horn 9 may be in communication with the passages through the tubular portions 12 and 16, or it may be cut off by means 85 of a swinging baffle 37 controlled by a knob 38.

There are illustrated preferred and satisfactory embodiments of the invention, but it is obvious that changes may be made therein 90 within the spirit and scope thereof, as defined in the appended claims.

What is claimed is:

1. In combination, a phonograph mechanism, a radio apparatus, a common amplifier 95 therefor, and means for guiding the sound from either the phonograph mechanism or the radio apparatus to the amplifier without passing to the other.

2. In combination, a phonograph mechanism, a radio apparatus, a common amplifier therefor, and means for guiding the sound from either the phonograph mechanism or the radio apparatus to the amplifier without 100 passing to the other, said means being adjustable so that the phonograph mechanism and the radio apparatus are in communication.

3. In combination, a phonograph mechanism, a radio apparatus, a common amplifier 110 therefor, means for guiding the sound from either the phonograph mechanism or radio apparatus to the amplifier without passing to the other, said means being adjustable so that the phonograph mechanism and the 115 radio apparatus are in communication, and means for cutting off communication between said phonograph mechanism and the amplifier, and between said radio apparatus and the amplifier.

4. In combination, a cabinet, a phonograph mechanism carried in the upper part of the cabinet, an amplifier below said mechanism and in communication therewith, a compartment in said cabinet having a movable panel forming a wall thereof, radio apparatus carried by the said panel within said compartment, and means forming sound communication between said radio apparatus and said amplifying means.

5. In combination, a cabinet, a phonograph mechanism in one part of the cabinet, an amplifier connected with said mechanism, a compartment in another part of the cabinet, a hingedly mounted panel forming one wall of the compartment, radio apparatus mounted upon said panel and having exposed control means at its forward side and radio elements concealed upon its inner side and means audibly connecting said radio apparatus with said amplifier, said panel being adapted to be swung to open position to expose said concealed elements. 70
6. In combination, a cabinet, a phonograph mechanism including an amplifier carried thereby, a compartment in said cabinet, a hingedly mounted panel forming one wall of the compartment, a radio apparatus mounted upon said panel within said compartment and having exposed control means at the forward side of the panel, means audibly connecting said radio apparatus with said amplifier, and closure means provided upon said cabinet for concealing said panel when the radio apparatus is not in use. 75
7. In combination, a cabinet, a phonograph mechanism including an amplifier carried thereby, a compartment in said cabinet, a hingedly mounted panel forming one wall of the compartment, a radio apparatus mounted upon said panel within said compartment and having exposed control means at the forward side of the panel, means audibly connecting said radio apparatus with said amplifier, and closure means provided upon said cabinet for concealing said panel when the radio apparatus is not in use, said panel being inset with respect to the front surface of the cabinet, and said closure means being substantially flush with said front surface. 80
8. In a radio-phonograph cabinet, the combination of a phonograph horn communicating with a tone arm, a sound tube mounted in fixed position within the cabinet and leading into said horn, a telephone receiver connected to the free end of said tube, and an adjustable valve for acoustically connecting said horn either with said tone arm or with both. 85
9. In a radio phonograph cabinet, the combination of a sound amplifying horn, a tone arm communicating therewith, a sound tube fixedly positioned within said cabinet and communicating with said horn, a radio receiver connected to the free end of said tube, and selectively adjustable means for acoustically connecting said horn either with said tone arm or with said tube. 90
10. In a radio phonograph cabinet, the combination of an amplifying horn, a tone arm communicating with said horn, a sound tube fixed in said cabinet and communicating with said horn, a sound box carried by said tone arm, a radio receiver carried by said sound tube, and selectively operable means for guiding the sound from either the sound box or the radio receiver to the amplifying horn without passing to the other. 95
11. In a radio phonograph cabinet, the combination of an amplifying horn, a tone arm communicating with said horn, a sound tube fixed in said cabinet and communicating with said horn, a sound box connected to said tone arm, a radio receiver connected to said sound tube, and a pivoted valve for acoustically connecting said horn either with said tone arm or with said tube. 100
